(57) **CLAIM**

The ornamental design for a vehicle cover, as shown and described.

DESCRIPTION

FIG. 1 is a top plan view of a vehicle cover showing our new design;

FIG. 2 is a left side elevational view thereof;

FIG. 3 is a right side elevational view thereof;

FIG. 4 is a front elevational view thereof; and,

FIG. 5 is a rear elevational view thereof.

In the drawings, the broken lines depict vehicle tires and logo indicators and form no part of the claimed design.

The “Neckline” at the top of the cover and “Signature Line” on the lower portion of the back of the cover are part of this claimed design.
